UNITED STATES PATENT OFFICE.

JOHN MACHENHEIMER, SR., OF NAUVOO, ILLINOIS.

CAR-COUPING.

SPECIFICATION forming part of Letters Patent No. 503,058, dated August 8, 1893.

Application filed May 6, 1893. Serial No. 473,322. (No model.)

To all whom it may concern:

Be it known that I, JOHN MACHENHEIMER, Sr., of Nauvoo, Hancock county, Illinois, have made a new and useful Improvement in Car-
5 Couplings, of which the following is a full, clear, and exact description.

The present invention relates to that class of car-couplings whose mechanism is adapted to be operated from the side of the car, and
10 it consists partly in the means for operating and controlling the movement of the coupling pin, and partly in the means for supporting the link, substantially as is hereinafter set forth and claimed, aided by the annexed
15 drawings, making part of this specification, in which—

Figure 1 is a side elevation of a car-coupling constructed according to the principle of the improvement, the draw heads being apart
20 from each other but as about to be closed together; Fig. 2 a plan of the parts as in Fig. 1; Fig. 3 a view similar to that of Fig. 1, but showing the draw heads closed together and coupled; Fig. 4 a vertical cross section on the
25 line 4—4 of Fig. 1; and Fig. 5 a vertical cross section, looking toward the left hand direction, upon the line 5—5 of Fig. 1.

The same letters of reference denote the same parts.
30 Only that portion of the coupling which is essential to an understanding of the improvement is exhibited.

A and A' represent the opposing draw-heads. The draw-heads, as well as the coupling pins B, B', and the coupling link C, are of the usual construction saving as modified or supplemented by the improvement under consideration.

D represents a device with which each draw-head is equipped, for upholding the link in a proper position to enable it to enter the opposing draw-head. It is adjustable so that it can be set out from the mouth of the draw head sufficiently to sustain the link in the de-
40 scribed position, and to be moved inward to be out of the way when the draw heads are being coupled. Its preferable form is shown, namely a rod shaped in the form of an elongated loop whose sides d, d', are held and
45 adapted to be moved longitudinally in bearings a, a', in the draw-head, and whose end,

d², constitutes the part upon which the link immediately rests, and whose inner portion, d³, is turned downward substantially as shown. The position of the link-support when moved 55 outward is shown in the left hand portion of Figs. 1 and 2, and its position when withdrawn is shown in the right hand portion of Figs. 1 and 2, and also in Fig. 3. The draw-head is recessed at a² to receive the outer end of 60 the link support when in its withdrawn position.

E represents a stop for limiting the outward movement of the link-support. The support is adapted to be operated by means 65 of ties F, F', which are connected with the support and lead thence to or toward the sides respectively of the car to enable the support to be adjusted by any one at the side of the car. The ties in question are connected with 70 the end bar or portion d³ of the support and lead thence around a bearing G which is attached to some suitable fixture such as the draw head, and thence in any suitable manner to or toward the sides of the car-body. 75 This last named part is not shown, as its construction is well understood, and its construction is not modified saving that it may be provided with any suitable support for the outer ends of the described ties. There are 80 two ties, F, F', employed, one of them leading to one side of the car, and the other of them to the opposite side of the car, and thus the operator at either side of the car is enabled to set the support in position for sus- 85 taining the link by drawing the tie which leads to the side of the car he is operating from. Each coupling pin is also adapted to be operated by means of a pair of ties H, H', as follows: these ties lead respectively from 90 the sides of the car to a bearing above the coupling-pins and thence downward to connect with the pins, and so that by drawing either of the ties the coupling pin can be elevated sufficiently to be free of the link. The 95 bearing, I, is of any suitable nature for sustaining the ties for the purpose in question. In the present instance it is in the form of an eye sustained by a standard, i, which in turn is supported by the draw-head. The 100 standard rises perpendicularly and the eye projects horizontally above the link substan-

tially as shown. The eye is at such a level as to cause the upper end of the pin to encounter it before the lower end of the pin has cleared the draw-head. The eye therefore 5 acts as a stop to prevent the pin from becoming detached from the draw-head. The ties H, H', below the bearing I, are preferably consolidated in the form of a single tie, H², substantially as shown.

- 10 In operation, the operator, from the side of the car at which he chances to be, draws the tie, F or F', and thereby causes the link support to be set out in position to sustain the link; this position is shown in connection 15 with the draw-head A, Figs. 1 and 2. Then as the opposing draw-head, A', approaches 20 he by means of the tie H raises the pin in that draw-head sufficiently for the link to enter; this position is illustrated in the draw- 25 head A', Figs. 1 and 2. The draw-heads can now close, and on coming together the link enters the draw-head A', and the link support D is, by reason of the drawhead A' encountering it, thrust backward out of the way and 30 into its position of Fig. 3. The operator by loosening the tie H allows the pin B' to drop and the coupling is thereby effected. The described operation can be performed, in an analogous manner, from the opposite side of 35 the car by operating the ties F', H'. The ties being in the nature of a cord or chain readily adapt themselves to the various positions not only of the parts with which they are immediately connected, but also of the draw heads, and thus provision is in a comparatively inexpensive manner made for 40 safely coupling and uncoupling railway cars. For, as is obvious, by drawing either of the

ties, H or H', belonging to a coupling pin the pin can be raised sufficiently to release 45 the coupling link in the draw-head to which the ties belong. It is also practicable as the draw-heads come together, for the same operator to adjust the link support and link of one of the draw-heads and also the coupling- 45 pin of the other of the draw-heads and thus accomplish the coupling of the draw-head.

I claim—

1. In a car-coupling, the combination of the draw-head, the longitudinally adjustable link-support, the bearing upon the draw-head, and the flexible ties leading from the link-support around said bearing, substantially as described.

2. In a car-coupling the combination of the draw-head, the longitudinally adjustable link-support, the stop for limiting the outward movement of the link-support, the bearing upon the draw-head, and the ties leading from said link-support around said bearing, 55 substantially as described.

3. In a car-coupling, the combination of the draw-heads, A and A', the coupling pins, the bearings respectively above said pins, the ties leading past said bearings to said pins re- 65 spectively, the adjustable link supports, the bearings upon said draw-heads respectively and the ties respectively leading from said link supports and around said bearings re- 70 spectively, substantially as described.

Witness my hand this 27th day of April, 1893.

JOHN MACHENHEIMER, SR.
